UNITED STATES PATENT OFFICE.

LUDWIG HEINRICH REUTER, OF NEW YORK, N. Y., ASSIGNOR TO BASIC CHEMICAL COMPANY, OF NEW YORK, N. Y., A CORPORATION.

SOAP.

No. 842,010.

Specification of Letters Patent.

Patented Jan. 22, 1907.

Application filed February 24, 1906. Serial No. 302,738.

To all whom it may concern.

Be it known that I, LUDWIG HEINRICH REUTER, a subject of the King of Bavaria, and a resident of the city of New York, borough of Brooklyn, in the county of Kings and State of New York, have invented a new and Improved Soap, of which the following is a full, clear, and exact description.

My invention relates to a soap having certain desirable qualities when used for toilet and medicinal purposes and in the arts.

The average soap of the market contains too much free alkali—so much, indeed, that it cannot be used without injury for toilet, medicinal, or technical purposes. On a large scale a neutral soap is not obtainable in one operation, and therefore practically all soap manufactured necessarily contains an excess of free alkali, which can only be removed in a second operation—for instance, by neutralization with an acid.

I have discovered that a practically neutral soap or soap solution of superior character and free from caustic alkali can be obtained if the free alkali be removed by means of a salt of a member of the magnesium group—for instance, of sulfate or borate of zinc or of magnesium.

In carrying out my process I add to an alkaline soap in liquid form a quantity of a salt of a member of the magnesium group which is equivalent to the quantity of free alkali present in the soap. The free alkali, whether in the form of hydroxid or carbonate, will enter upon a double decomposition and will precipitate an equivalent quantity of the hydrate of the respective member of the magnesium group if alkali is present, or of the basic carbonate if alkali carbonate is present, while forming at the same time a salt of the alkali. If sulfate of zinc is used to neutralize soap containing free alkali hydrate, alkali sulfate and hydrate of zinc will be formed.

When the soap contains, as the result of its being exposed to the air for a long time, in-

stead of alkali hydrate, alkali carbonate, the following reaction takes place:

If a salt of another member of the magnesium group is used, similar results will follow—as, for instance, with sulfate or sulfocarbonate of magnesia, sulfate or sulfocarbonate of the alkali and magnesium hydrate will be formed. When borate of magnesium is being used, magnesium hydrate and alkali borate will be formed, and the small quantity of the latter tends to improve the quality of the soap. I have found that all the soluble salts of zinc and magnesium, also borate of magnesium, freshly prepared, can be used advantageously, while borate of zinc, being insoluble, yields results only when the mixture of the same with the alkaline soap is macerated for some time at water-bath temperature to complete its transformation into alkali borate and zinc hydrate, respectively.

As an example of manufacture I determine first the percentage of free alkali contained in the soap which is to be neutralized and then I dissolve a suitable quantity of it—say, for instance, forty pounds—in eight to nine gallons of water. As soon as the soap is dissolved I add, if the soap was found to contain 1.5 per cent. free alkali—for instance, as potassium hydrate, equivalent to a total quantity of 0.6 pounds potassium hydrate—1.54 pounds of crystallized sulfate of zinc ($\text{ZnSO}_4 + 7\text{H}_2\text{O}$) or of a proportionate quantity of any other salt of a member of the magnesium group, dissolved in a suitable quantity—say, for instance, in five pints or more of water. Then I heat the liquid, constantly stirring in the water-bath, until the reaction is finished—viz., until all the free alkali has been converted into a salt and zinc hydrate. From time to time samples are taken, filtered, and tested to see if all free alkali has been removed, and if that is not the case some more of the solution of sulfate of zinc is added. Finally the liquid soap thus obtained can be converted in the usual way into dry soap. In this case the zinc hydrate can be left in the soap, or, if liquid soap is desired, the liquid obtained in the above process may be mixed with

suitable quantities of water or water and glycerin or any other alcohol and filtered for the purpose of removing the zinc hydrate. For making a stable liquid soap it might be 5 preferable also to saponify suitable fats or oils, properly those containing oleic acids, with caustic alkali, for instance, with caustic potash in the usual way, dissolve the finished soap in water or a mixture of water and alcohol or water, alcohol, and glycerin, neutralize by heating the liquid with a solution of a salt of magnesium or zinc, discharge the liquid soap in a tank, allow the same to settle for some time, and filter finally through 15 cloth or otherwise under pressure in a suitable filtering device.

The use of salts for the purpose of removing the free alkali is, I believe, entirely new. The process has, unlike that in which 20 acids are used for neutralization, the advantage that no free fatty acids could be formed or separated if an unskilled hand should handle the process carelessly and would use a little more of the neutralizing agent than 25 absolutely necessary. All that could happen would be the precipitation of some oleate of zinc or magnesium easily removable by filtration if liquid soap was to be made and perfectly harmless or rather improving the 30 quality if left in soap stock for solid soap.

A great advantage of the above-described new process is its cheapness and the fact

that it can be applied easily to ton lots of soap without any risk whatever.

Soaps obtained as described are neutral, 35 and there is no objection to their application in cases where the use of alkaline soaps would have been dangerous. Neutral soaps made in accordance with the above new process will not, in fact, injure the most delicate skin 40 or scalp, they can be used without producing any irritation for cleaning and dressing wounds, they will not have any injurious effect on the fiber of fine textiles and fabrics and will not produce any discoloration of the 45 same, and they will be a valuable addition to the *materia medica*, to the laboratory of the textile worker, and they are finally of value for household and for laundries.

Having thus described my invention, I 50 claim—

The method herein described, which consists in adding to alkali soap a quantity of a salt of zinc sufficient to neutralize the free alkaline in the soap, heating the liquid, and 55 converting the liquid into dry soap.

In testimony whereof I have signed my name to this specification in the presence of two subscribing witnesses.

LUDWIG HEINRICH REUTER.
